UNITED STATES PATENT OFFICE.

ROY L. DE CAMP, OF LOS ANGELES, CALIFORNIA, ASSIGNOR TO BAKER IRON WORKS,
OF LOS ANGELES, CALIFORNIA, A CORPORATION OF CALIFORNIA.

SAFETY DOOR INTERLOCKING SWITCH.

1,356,698.

Specification of Letters Patent. Patented Oct. 26, 1920.

Application filed September 25, 1917. Serial No. 193,188.

To all whom it may concern:

Be it known that I, ROY L. DE CAMP, a citizen of the United States, residing at Los Angeles, in the county of Los Angeles and State of California, have invented a new and useful Safety Door Interlocking Switch, of which the following is a specification.

This invention pertains to switches of the character designed to be operated by closing and opening movements of a closure or other member and an object of the invention is to produce a device of this character of minimum liability to become disarranged, and requiring minimum attention to keep in operative condition.

Another object is to construct a switch of which the operating member thereof interlocks with a member mounted on the door.

Another object is to so construct the switch that the parts thereof will not be subject to blows or shocks when the door is opened and closed.

Other objects and advantages will appear in the subjoined detail description.

The accompanying drawings illustrate the invention.

Figure 1 is a fragmental front elevation of a door structure with the newly invented switch applied thereto, the door being shown in open position in solid lines and in closed position in broken lines.

Fig. 2 is an enlarged side elevation of the switch shown in Fig. 1, the operating member being in section. Solid lines indicate the operating member and switch arm in circuit-breaking position and broken lines indicate said member and arm interlocked in circuit-closing position.

Fig. 3 is a sectional elevation on line indicated by x^s-x^s , Fig. 2.

Fig. 4 is a side elevation of the switch, the cover and switch arm being omitted to expose to view the inside mechanism of the switch.

Fig. 5 is a reduced plan section on line indicated by x^s-x^s , Figs. 2 and 4.

The invention is designed to be used in connection with any suitable closure and is especially adapted to be used in connection with elevator doors, and a door of this description is indicated at 1 in Fig. 1. The door 1 is provided with an operating member of any suitable construction and in the drawings said member is shown in the form of a pin 2 of circular cross section. The pin

2 is adapted to engage a T-shaped switch arm, said arm having laterally extending members or limbs 3, 4 and a central rib 5 substantially at right angles to the members 3, 4. The rib 5 and limb 3 or limb 4 together form an L-shaped arm. At the junction of the members 3, 4 with the rib 5 are offset notches a , b respectively, said notches being of suitable shape to fit the operating member 2 and in the instance shown, curved to fit said member. The switch arm also includes a flange 6 connecting the members 3, 4 to a hub 7 of said switch-operating arm. The hub 7 fits loosely on the outer projecting end of a stud 8 which is tightly inserted in an internal boss 9 of a switch case 10, there being a shoulder 11 on the stud 8 seated against the boss 9. The side of the case 10 opposite the boss 9 is formed by a removable cover 12 fastened in place by screws 13 or equivalents and provided with a central orifice 14 to accommodate the inner end of the hub 7.

The hub 7 rests against the outer face of a drum 15 which is circular excepting as hereininafter noted and which is constructed of any suitable electric-insulating material, the drum 15 being keyed to the hub 7 so as to be rotated by turning of the switch-operating arm. In the instance shown in the drawings the keying of the drum 15 to the hub 7 is accomplished by pins 16 projecting from the hub 7 into sockets 17 formed in the drum 15 as clearly shown in Fig. 5. Thus when the switch-operating arm is turned the hub 7 and drum 15 are rotated on the stud 8. A washer 18 is preferably interposed between the stud shoulder 11 and the drum 15 as shown in Fig. 3 and the washer 19 is placed on the outer end of the stud 8 against the outer face of the hub 7. The washer 19 is held against outward displacement by any suitable means, in the instance shown in the drawings said means comprising a cotter pin 20 inserted through a transverse hole 21 in the stud 8.

The drum 15 is provided on its curved periphery with semi-circular contact members 22, 23 mounted opposite to one another and fastened to the drum by any suitable means such, for instance, as screws 24. The drum 15 is cut away at one side to form a flat face 25 along which extends a connector 26 which may be in the form of a copper strip or equivalent and which has its 110

ends inserted between the drum and the contacts 22, 23, two of the screws 24 passing through the ends of the connector 26 to firmly hold it in place.

- 5 When the drum 15 is turned sufficiently, the contacts 22, 23 are adapted to be engaged by other contact members 27, 28, each of which comprises a straight portion 29, an inwardly bent inwardly convex or 10 semi-circular portion 30, and an end flange 31 engaged in a transverse groove 32 of an angular bracket 33. There are two brackets 33 and each is fastened by screws or equivalents 34, 35 to an insulating member 15 36 which in turn is fastened by screws or equivalents 37 to the case 10. The screws 35 project out sufficiently far beyond the inner face of the brackets 33 to form binding posts and on said binding posts are mounted 20 washers 38 having semicircular outturned flanges 39. Binding nuts 40 on the screws 35 may be turned up to hold the leads, not shown, by which the switch is electrically connected in the control circuit of the elevator or other circuit to be closed and opened by operation of the switch. Means are provided to yieldingly hold the contacts 27, 28 with their curved portions 30 in engagement 25 with the contacts 22, 23 when the drum is turned sufficiently far for that purpose and such means are constructed as follows, though it is understood that they may be otherwise constructed if desired. The straight portion 29 of each contact member 30 27, 28 is provided with a perforation 41 to receive a headed pin 42 which projects through a perforation 43 in the bracket 33, the head of the pin being at the outer face of the straight portion 29. Each pin 42 is 35 provided with washers 44 and coil springs 45 between the washers, said washers and springs being held in place by cotter pins 46 passing through holes 47 in the pins 42. The expansive force of the springs 45 pulls 40 the heads of the pins 42 against the contacts 27, 28 so as to force the contact portions 30 toward the drum 15 as is clearly understood.

It is now clear that when either of the 50 contacts 22, 23 are in engagement with the contact 27 electric current will flow between the binding posts 35.

From the foregoing it is clear that the switch is readily assembled and disassembled for, by removing the cotter pin 20, the washer 19, hub 7 and drum 15 may be slipped off of the stud 8, and by removing the cotter pins 46 the pins 42 may be withdrawn from the perforations 41, 43 so as to 60 release the contacts 27, 28.

Assuming that the binding posts 35 are connected in the circuit controlling the operation of an elevator, it is clear that when the elevator door 1 is in the unclosed 65 position shown in solid lines in Fig. 1 the

electric circuit will be broken and that in order for the operator to close the circuit so as to operate the elevator car it will be necessary for the door to be closed as in broken lines in Fig. 1 so as to swing the 70 switch-operating arm 4 sufficiently far to cause engagement of the contact 27 with the contact 22.

As the pin 2 moves to the left in Fig. 2 it is clear that said pin interlocks with the 75 switch-operating arm by reason of the offset, notch *a*, as clearly shown in broken lines *c*, Fig. 2. It is also clear that when the door 1 is opened the pin 2, because of its interlocking with the switch-operating arm, will 80 open the switch. Thus it is clear that opening movement of the switch-operating arm as well as closing movement thereof is effected by movement of the elevator door and not through the agency of any spring, 85 weights or by gravity.

In devices of this character it is of prime importance that the switch operating means co-operate with the switch in such a manner as to prevent overthrow or backlash, for the 90 reason that the closures to which said device may be applied, are at times forcibly slammed shut with a consequent perceptible rebound. The switch arm must therefore co-operate with the operating pin in such a manner as to retain said arm against overthrow when forcibly engaged by the pin and also in such a manner that the arm will be immediately effected by any rebound movement of said pin. 95

In the present construction one of the offset notches closely engages the operating pin 2 during a switch operating movement thereby effectively preventing overthrow of the switch arm ahead of the pin when said 105 pin engages the arm with great force and also transmitting any rebound movement of the pin to the switch arm, so that the switch will not be closed with the door still in partly open position, due to a rebound 110 thereof.

The switch parts are shown in the drawings as being assembled in positions suitable for use with a door opening to the right, but the construction of the switch provides 115 for assembling the parts in position so that the switch can readily be used for a door opening to the left and such assembling is done as follows: The switch-operating arm 3, 4, 5, 6, 7 will be operated in a reverse direction from that shown in Fig. 2 and it is clear that when the switch is placed in position in connection with a door opening to the left the pin 2 in said door will engage the notch *b* instead of the notch *a*. 120

It may be desirable under some conditions of installation to place the switch case above or beneath the closure and for this reason the drum 15 may be provided with holes 48 so that the switch-operating arm can be 130

turned 90 degrees relative to the drum and the pins 16 will then seat in the holes 48.

In operation, rotation of the drum causes wiping or rubbing engagement of the contacts 22, 23, 27, 28 thus cleaning the contacts of any foreign matter inimical to closing of the electric circuit.

It is noted that cutting away of the drum to form the flat face 25 produces an air gap between the contact portion 30 and the drum thus increasing the insulating of the contact portion 30 from the connector 26.

It is understood that the various parts above specifically described may be otherwise constructed within the spirit and scope of the appended claims.

From the foregoing it is clear that the switch is mechanically and positively operated to close and break the circuit by the operation respectively of closing and opening the door and is not dependent upon springs, weights or gravity, thus making it impossible to open the door without opening the elevator controlling circuit and to close the door without closing the circuit.

I claim:

1. The combination with a closure having a pin projecting therefrom, of a switch having an L-shaped operating arm provided with an offset notch at the junction of its limbs to fit the pin.
2. The combination with a closure having a pin projecting therefrom, of a switch having a pivotally mounted L-shaped operating arm provided with an offset notch at the junction of its limbs to fit the pin.

3. A switch comprising a rotatively mounted drum, contacts mounted on said drum, other contacts, means to yieldingly hold said other contacts toward the drum, and an L-shaped arm connected with the

drum to turn the drum, said arm having an offset notch at the junction of its limbs for engagement with an operating member.

4. The combination with a closure having a switch-operating member projecting therefrom, of a switch having a reversibly mounted arm provided with a pair of offset notches to fit the switch-operating member.

5. The combination with a closure having a pin projecting therefrom, of a switch having a pivoted operating arm comprising angularly arranged members, one of said arm members being parallel to the path of movement of the pin when the closure is in open position and the other arm member extending at the same time vertically across the path of movement of said pin, there being an offset notch at the junction of said arm members adapted to receive a portion of the pin as the closure moves from open to closed position.

6. The combination with a closure having a pin projecting therefrom, of a switch having a reversibly pivoted T-shaped operating arm, two of the limbs of said arm being parallel to the path of movement of the pin when the closure is in open position and the other limb of the arm at the same time extending vertically across the path of movement of the pin, there being an offset notch at the junction of the vertical limb with each of the other limbs adapted to receive a portion of the pin as the closure moves from open to closed position.

Signed at Los Angeles, California, this 7th day of September, 1917.
